(57) CLAIM

The ornamental design for a garment hook, as shown and described.

DESCRIPTION

FIG. 1 is a front perspective view of a garment hook showing my new design;

FIG. 2 is a rear perspective view thereof;

FIG. 3 is a front elevational view thereof;

FIG. 4 is a top plan view thereof;

FIG. 5 is a left end elevational view thereof, with a right end elevational view being a mirror image thereof; and,

FIG. 6 is a bottom plan view thereof.

The broken lines shown represent unclaimed subject matter and form no part of the claimed design.
